UNITED STATES PATENT OFFICE.

FRANK C. OSBORN, OF CLEVELAND, OHIO.

LIFTING MECHANISM FOR BRIDGES.

1,158,546.

Specification of Letters Patent.

Patented Nov. 2, 1915.

Application filed October 31, 1913. Serial No. 798,398.

To all whom it may concern:

Be it known that I, FRANK C. OSBORN, a citizen of the United States, and a resident of Cleveland, county of Cuyahoga, and State of Ohio, have invented a new and useful

5 Improvement in Lifting Mechanism for Bridges, of which the following is a specification, the principle of the invention being herein explained and the best mode in which I have contemplated applying that principle, so as to distinguish it from other inventions.

10 The subject of the present invention is an improved lift bridge in which the usually unreliable and often dangerous cable members have been simplified into an extremely strong and heavy connection between the bridge to be lifted and the counter-weight, and one which is freely movable over a properly constructed supporting tower. 15 Railroad engineers have long objected to the use of cables for these reasons and have never been satisfied with them in bridges, although nothing better is known.

20 It has long been known that flexible cables were extremely dangerous when used in lifting bridges, as they wear very unevenly on the sheaves and often cause serious accidents, but no method of overcoming this difficulty was hitherto found. The present invention, however, does away with these dangers and at the same time simplifies the general construction to a considerable extent.

25 To the accomplishment of the foregoing and related ends, said invention, then, consists of the means hereinafter fully described and particularly pointed out in the claims.

30 The annexed drawing and the following description set forth in detail certain mechanism embodying the invention, such disclosed means constituting, however, but one of various mechanical forms in which the principle of the invention may be used.

35 In said annexed drawing:—Figure 1 is an end elevation showing one of the towers over which the connecting cable moves; Fig. 2 is a plan view showing the connection between two of the links of the cable; Fig. 3 is a section through the track formed on top of the tower; Fig. 4 is a section through the modified type of track; Figs. 5 and 6 are similar sections showing other modifications of this feature; and Figs. 7 and 8 show modifications of other features.

In Fig. 1 I have shown a tower 1 in which the mechanism for raising the bridge is adapted to be housed, such tower consisting briefly of two spaced parallel upright supports 2 connected by means of a member 3 for steadiness and bearing upon their upper ends two complementary trusses 4, which, when in position, conjointly form a semi-circular arch over the uprights of the tower. 40 This arch should be of substantial size to distribute the weight carried thereby. If only the usual lifting mechanism were provided with this construction, still a very important advantage would be secured, since each tower has been simplified until it consists of but five members, whereas in the usual construction there are a much larger number, including bearings, etc., for the large sheaves which operate the cables. The 45 bridge 5 to be lifted will be placed between two such towers and in line with the same of course, and will be attached at either end to cables 6 which extend up along the side of one upright, then over the arch and 50 finally down the side of the other upright where it is terminally connected with a suitable counter-weight 7.

The cable 6 will preferably comprise a plurality of links 8, preferably in the form 55 of I-bars or some equivalent construction, of equal length, which at their extremities are pivotally connected to each other by means of pins 9 which extend from either side of rollers 10, such rollers being adapted to 60 rest upon the curved surface 11 of the arch and move freely thereover. It will be apparent that the rollers must be of sufficient size to prevent contact between the body of the link and the surface of the arch, as otherwise there would be a certain dragging 65 which would prevent free rolling of the cable. The necessary size of the rollers will depend of course upon the length of the links, and the shorter the links the smaller 70 the diameter of the rollers.

The precise form of the curved surface of the arch, or the track or roller-way as it may be called, is of little importance so long as some means are provided to effectually prevent the cable from running off the track. Thus the track-way may take the form shown in Fig. 3 in which there are provided flanges 12 on either side between which the rollers operate, or it may be constructed as 75 in Fig. 4, in which case a central ridge or projection 13 is provided engaging in a com-

plementary groove 14 in the rollers. Other possible constructions are those shown in Figs. 5 and 6 in which the track is beveled slightly, the rollers of course being correspondingly formed to properly engage in the track.

The precise form of the links is similarly of little importance, it being possible to provide a single roller at the juncture of the links or to provide what may be termed a truck 15 in which two, or even three, rollers 10 may be held. Such constructions are shown in Figs. 7 and 8 where there is a truck consisting of a member 15 bearing two parallel rollers 10 and being connected to the links at either side. These various details of construction may be changed to suit the individual conditions, the main features of the invention being of course the construction of the support which permits of the use of a rolling chain or cable such as has been described.

Other modes of applying the principle of my invention may be employed instead of the one explained, change being made as regards the mechanism herein disclosed, pro-

vided the means stated by any of the following claims or the equivalent of such stated means be employed.

I therefore particularly point out and distinctly claim as my invention:—

1. In a lift bridge, the combination of an elevated arch of substantial radius, a cable passing over said arch and provided with rollers which ride thereon, a bridge connected to one end of said cable and a counterweight secured to the other end thereof.

2. In a lift bridge, the combination of an elevated arch of substantial radius, a cable passing over said arch and provided with rollers which ride thereon, means for guiding said rollers on said arch, a bridge connected to one end of said cable, and a counterweight connected to the other end thereof.

Signed by me, this 28th day of October, 1913.

FRANK C. OSBORN.
